CLAIM

The ornamental design for a remote keeper, as shown and described.

DESCRIPTION

FIG. 1 is a perspective view from above of my new design for a remote keeper.

FIG. 2 is top plan view of the remote keeper of FIG. 1.

FIG. 3 is a back elevational view thereof.

FIG. 4 is a front elevational view thereof.

FIG. 5 is an elevational view of one side thereof.

FIG. 6 is an elevational view of the opposite side thereof; and, FIG. 7 is a bottom plan view thereof.

The broken line showing of remote device is included for the purpose of illustrating environment of the article and forms no part of the claimed design.
